DIP NET OR SIMILAR ARTICLE

James W. Harvey, Lakeville, Conn.

Application March 5, 1949, Serial No. 1,231

Term of patent 14 years

(Cl. D31—4)

To all whom it may concern:

Be it known that I, James W. Harvey, a citizen of the United States of America, residing at Lakeville, county of Litchfield, State of Connecticut, have invented a new, original, and ornamental Design for a Dip Net or Similar Article, of which the following is a specification, reference being had to the accompanying drawing, forming part thereof.

Fig. 1 is a perspective view of a dip net or similar article, showing my new design.

Fig. 2 is a front face view of the handle with a portion of the net frame broken away for convenience, the rear face having the same appearance.

Fig. 3 is an edge view of the handle with a portion of the net frame broken away.

The characteristic features of the design reside in the portion shown in full lines.

I claim:

The ornamental design for a dip net or similar article, as shown and described.

JAMES W. HARVEY.
